CLAIM

The ornamental design for a container for drilling core,
as shown and described.

DESCRIPTION

FIG. 1 is a top, rear and right side perspective view of
a container for drilling core showing my new design;
FIG. 2 is another perspective view showing the con-
tainer open;

FIG. 3 is a side elevational view thereof, the opposite
side being identical to the side shown;

FIG. 4 is a front elevational view thereof;

FIG. 5 is a top plan view thereof;

FIG. 6 is a rear elevational view thereof; and

FIG. 7 is a bottom plan view thereof.
